ATTORNEY

UNITED STATES PATENT OFFICE

JOSEPH I. PADGETT, OF JACKSONVILLE, FLORIDA

SKATE

Application filed August 21, 1931. Serial No. 558,566.

The invention relates to skates and more particularly to the class of roller skates.

The primary object of the invention is the provision of a skate of this character wherein there is arranged a single roller at the toe end and a pair of wheels at the rear or heel end, the said roller and wheels being rubber tired and such rear wheels are controllable through braking mechanism, where-
10 by the speed of the skate can be reduced and also the latter brought to a standstill.

Another object of the invention is the provision of a skate of this character, wherein the construction thereof is novel in form and
15 has in association therewith braking mechanism operable by the user of the skate at will, the assembly of the braking mechanism with the rear wheels of the skate being unique and also novel in form.

20 A further object of the invention is the provision of a skate of this character wherein the heel seat is yieldably suspended in a stirrup and the rear wheels of such skate carry mud guards or fenders so as to pro-
25 tect the user of the skate during the use thereof in inclement weather or passing over mud covered surfaces or water puddles.

A still further object of the invention is the provision of a skate of this character
30 which is extremely simple in construction, thoroughly reliable and efficient in its purpose, neat and attractive in appearance, readily controllable by the user thereof, and inexpensive to manufacture.

35 With these and other objects in view, the invention consists in the features of construction, combination and arrangement of parts as will be hereinafter more fully described in detail, illustrated in the accompanying drawings, which disclose the preferred em-
40 bodiment of the invention, and pointed out in the claim hereunto appended.

In the accompanying drawings:

45 Figure 1 is a side elevation of a skate constructed in accordance with the invention.

Figure 2 is a top plan view.

Figure 3 is a vertical longitudinal sec-
50 3—3 of Figure 2.

Figure 4 is a sectional view on the line 4—4 of Figure 2.

Figure 5 is an enlarged detail sectional view through the bearings of one of the rear wheels of the skate.

Figure 6 is a sectional view on the line 6—6 of Figure 3.

Figure 7 is a detail perspective view of one of the parts of the brake assembly.

Similar reference characters indicate cor-
60 responding parts throughout the several views in the drawings.

Referring to the drawings in detail, the skate comprises shoe sole and heel plates 10 and 11 respectively which are adjustably carried upon a connecting bar 12, the heel plate 11 being marginally rimmed as at 13 to provide a seat for the heel of the shoe of the user of the skate. The plates 10 and 11 are provided with adjustable straps 14 and 15 respectively for the securing of the skate upon the wearer.

Secured to the forward portion of the bar 12 beneath the same is a yieldable brace 16 which is suitably connected at its rear portion medially with a stirrup 17, while interposed between the bar 12 and said brace 16 beneath the heel plate 11 is an elliptical-shaped spring 18, the latter being disposed transversely with relation to the bar and brace.

At the front end of the skate is a rubber tired roller 19, the hanger 20 of which is rotatably secured to the bar 12 and brace 16 by a bolt 21 carrying a nut 22, the head 23 of said bolt 21 being countersunk in the bar 12 to underlie the plate 10 and surrounding this bolt 21 is a coned ball bearing 24 and this roller 19 constitutes the guide or steering roller for the skate.

The stirrup 17 is formed with outturned axles 25 on which are journaled rear wheels 26 having rubber tires 27 and in the hubs 28 of said wheels are bearing balls 29. The wheels 26 are formed with brake drums 30 with each of which coacts an expandible brake band 31 for braking purposes. The band 31 has associated therewith coiled re-
95 tractile springs 32, these serving to retract the band for freeing the wheel, said band 100

being split and having at the confronting ends of said split abutments 33 between which is disposed a cam 34, there being one for each brake band, these are carried on a yoke 35 5 swingingly supported in mud or fender guards 36 overhanging the wheels 26 and made fast in this position with the stirrup 17.

On the swinging of the yoke 35 in one direction the cams 34 will be operated to expand the brake bands 31 against the brake 10 drums 30 and in this fashion the skate can be controlled as to the speed of travel thereof.

The yoke 35 has connected thereto a pull cable 37 which can be fastened to a belt of 15 a person or engaged by the hand of such person so that the brake can be manually operated as will be obvious.

The skate is usable as an ordinary roller 20 skate and the control of speed or travel thereof is effected through the cable 37 and the braking mechanism hereinbefore described.

What is claimed is:—

In a skate having a front steering roller and a pair of rear wheels, brake mechanism 25 connected to the rear wheels, a swinging yoke connected to the braking mechanism, manually operable pull means connected to the yoke, a stirrup arranged between the rear wheels, and a heel piece yieldably suspended 30 in the stirrup.

In testimony whereof I affix my signature.
JOSEPH I. PADGETT
